Albert Dillon,

UNITED STATES PATENT OFFICE.

ALBERT DILLON, OF AITCH, OHIO.

NUT-LOCK.

1,134,596.

Specification of Letters Patent.

Patented Apr. 6, 1915.

Application filed July 23, 1913. Serial No. 780,802.

To all whom it may concern:

Be it known that I, ALBERT DILLON, citizen of the United States, residing at Aitch, in the county of Monroe and State 5 of Ohio, have invented certain new and useful Improvements in Nut-Locks, of which the following is a specification.

This invention relates to new and useful improvements in nut locks and it has 10 particular reference to a nut lock of that type which includes a removable key carried by the bolt and formed for engagement with grooves cut into the bolt and nut.

It is a further object of the invention to 15 facilitate the locking and unlocking of the nut without damage to either of these members, and thereby to provide for the repeated use of both the bolt and nut.

The above and additional objects are 20 accomplished by such means as are illustrated in their preferred embodiment in the accompanying drawings, described in the following specification and then more particularly pointed out in the claim which is appended hereto and forms a part of this application.

In describing my invention in detail reference will be had to the accompanying drawings wherein like characters denote 30 like or corresponding parts throughout the several views, and in which:—

Figure 1 is a side elevation of a nut lock constructed in accordance with my invention; Fig. 2 is a section on the line 3—3 of 35 Fig. 1; Fig. 3 is a section on the line 2—2 of Fig. 1; Fig. 4 is a detail elevation of the locking key or member, partly broken away; and Fig. 5 is a longitudinal sectional view of a portion of the bolt and key illustrating the manner in which the latter is 40 retained in proper place.

Referring now to the drawings, wherein is illustrated the embodiment of my invention the numeral 1 designates a bolt of ordinary construction having the usual threaded portion 2 formed upon one end thereof. Diametrically opposite grooves 3 are formed within the threaded portion 2 of the bolt the said grooves being connected by a transverse groove 3' extending across the outer 50 end of the bolt shank 1. Nuts 4 and 5 respectively are adapted to be threaded or screwed upon the threaded portion 2 of the bolt and locked thereupon in a manner to be hereinafter fully described. Oppositely disposed grooves 6 and 7 are formed re-

spectively within the nuts 4 and 5, the said grooves, when the nut is threaded over the shank 2 of the bolt, adapted to receive a key member 8 which is in turn inserted or forced into the grooves 3 of the bolt, the edges of the said key projecting beyond the periphery or outer face of the bolt shank. The said key member 8 is split centrally from its inner end thereby forming arms 8' disposed to straddle the threaded portion 2 of the bolt; the connecting portion of the key designated 9' fitting within the transverse groove 3' of the said bolt.

For the purpose of locking the key 8 against accidental removal, a cotter pin 9 is provided, one portion of the pin being inserted or forced into an opening 10 formed within the extremity of the bolt shank so as to extend therethrough in a direction transverse to the groove 3' above mentioned, that portion of the key member fitting within the said groove 3' having an opening 11 formed therein adapted to register with the said opening 10 as illustrated to advantage in Fig. 5 of the drawings. A larger opening 12 is formed within the key member 8 adjacent the opening 11, through which the other portion of the cotter pin 9 is inserted, this arrangement of 85 the pin with respect to the key and bolt locking the former against lateral as well as longitudinal movement independent of the bolt itself.

The grooves 6 and 7 of the nuts are 90 formed in uniform spaced relation and extend throughout the entire length of the central bore or opening of the said nuts, this arrangement of the grooves permitting the key member 8 to be placed and removed 95 after the said nuts have been properly adjusted upon the threaded portion 2 of the bolt.

It will be seen from the above, taken in connection with the accompanying drawings 100 that the removal of the pin 9 and the withdrawal of the key member 8 from the slots 3 of the bolt shank, will permit the nuts 5 and 6 threaded thereon to be either entirely removed or freely adjusted as occasion demands; and that the removal of the said pin and key will in no way injure or prevent a second or repeated use of both the nuts and bolt.

It will be understood that the above description and accompanying drawings comprehend only the general and preferred

embodiment of my invention and that various minor changes in details of construction, proportion and arrangement of parts may be made within the scope of the appended 5 claim and without sacrificing any of the advantages of my invention.

Having thus fully described my invention, what I claim as new and desire to secure by Letters Patent, is:—

- 10 In a nut lock, a grooved bolt, a grooved nut, said grooves forming key ways, a substantially flat locking key comprising a head portion having two openings formed therein, arms extending therefrom in parallel 15 spaced relation, said arms fitting said ways,

said head portion fitting a transverse groove connecting said bolt grooves, and a locking pin of the cotter type, one of the extensions of which is insertible within an opening of the bolt and one of the openings of said head, the other of the said extensions being insertible within the other of the said head openings exteriorly of the bolt, as and for the purpose set forth.

In testimony whereof I affix my signature 25 in presence of two witnesses.

ALBERT DILLON.
